UNITED STATES PATENT OFFICE.

PAUL BRANDSTEDT, OF WASHINGTON, DISTRICT OF COLUMBIA.

METAL STUDDING OR PARTITION.

SPECIFICATION forming part of Letters Patent No. 694,721, dated March 4, 1902.

Application filed June 24, 1901. Serial No. 65,833. (No model.)

To all whom it may concern:

Be it known that I, PAUL BRANDSTEDT, residing at Washington, in the District of Columbia, have invented a new and Improved 5 Metal Studding or Partition, of which the following is a description.

This invention relates generally to a fire-proof building construction, and more specifically to an improved metallic member adapted to serve as a stud or ceiling-support, having means for conveniently attaching metal laths thereto; and primarily this invention seeks to provide a stud or supporting member for the purposes stated of a very simple 10 and inexpensive construction, capable of being conveniently handled and set up for use, and to effectively serve for its intended purposes.

In its generic nature my invention comprehends a corrugated sheet-metal member having two opposite edges equipped with lath-clamping members to receive the lathing from either or both sides and a securing member at the lower end for making fast to the floor 20 joist or beam, upon which it rests, and means at the upper end whereby it can be conveniently made fast to the ceiling-joist or I-beam without the use of nails or other separate fastening means.

My invention in its more specific nature also embodies, in a metal stud having means for making fast at the lower end, an upper extensible section having specially-formed 30 portions for connecting with the ceiling-joists or I-beams and having its lower portion provided with slots adapted to receive clamp ends of metallic bridging-sections forming a coöperative part of my improved construction of studding, or when used as partition 35 member and to receive hangers for sustaining the same from overhead I-beams or joists when used as a ceiling-support.

Again, my invention has for its purpose to provide an improved form of metallic stud or 40 ceiling member adapted for use against a solid wall as a partition member or as a supporting means for the hanger-rail of sliding doors or partitions.

In its more subordinate features my invention 45 consists in certain details of construction and peculiar combination of parts, all of which will hereinafter be fully explained, and par-

ticularly pointed out in the appended claims, reference being had to the accompanying drawings, in which—

Figure 1 is a view illustrating my invention adjusted for use as a stud or partition structure. Fig. 2 is a horizontal section of the same as applied for use against a solid wall to receive lathing on one side only and embedded in a solid layer of plaster. Fig. 3 is a similar section showing the same used as a partition-stud to receive the plaster on both sides. Fig. 4 is a perspective view of one of the metallic sections with the extensible section. Fig. 5 is a view of the extensible section detached. Fig. 6 is a cross-section substantially on the line 6 6 of Fig. 4. Fig. 7 is a view illustrating my invention arranged to act as a ceiling-support. Fig. 8 is a side elevation of one side of a portion of the stud or supporting member. Fig. 9 is a vertical section thereof, taken substantially on the line 9 9 of Fig. 8 and showing the manner of clamping a lath thereon. Fig. 10 is a view 75 of a modified form of my invention. Fig. 11 is a detail horizontal section on the line 11 11 of Fig. 1. Fig. 11^a is a detail section on the line a a of Fig. 11. Figs. 12 and 12^a are views illustrating the manner of arranging my improved stud for supporting the hanger or rail for sliding doors or partitions.

Referring now to the accompanying drawings, in which similar letters indicate like parts in all the figures, 1 designates my improved metal member, which is formed of sheet-iron and which to provide for strength, rigidity, and great tensile strain is corrugated or pressed up into the shape shown in the several horizontal sectional views thereof, by reference to which it will be noticed the same consists of a metal plate bent centrally in the direction of its length into a U shape, the sides 2 2 of the body being bent back in parallel vertical planes to produce two opposite flat surfaces 3 3, adapted to receive the lathing, which by reason of the flat surfaces 3 3 can be placed against either or both of the sides 2 2 and to provide for conveniently, quickly, and effectively securing the laths 95 4 4 to the stud or supporting member 1, the faces 3 3 having diagonal slots 3^a 3^a, which extend through the free ends of the sides 3 3, whereby to produce bendable clip mem-

bers 3^b 3^c, adapted to be bent over the laths, as clearly shown in Fig. 9, and thereby firmly clamp them upon the sides of the studs without the use of nails or other additional fastening means. It is manifest that by bending that part of the body portion between the parallel sides 2 2 inward, as shown and described, the member 1 is rendered one of great strength and rigidity, and the sides thereof will have sufficient resiliency to permit of a limited expansion or contraction thereof without affecting the complete construction of the partition.

In the simplest form—that is, when the stud 15 or member 1 is specially made and of a desired length—the lower end of the U-shaped body portion is extended in a flattened condition and bent inward at right angles to produce a footpiece 6 for resting upon the floor, 20 to which said piece 6 may be secured by spikes or screws; but when the stud is to be used in connection with I-beams above and below the sides 2 2 are extended at both ends, as at 7^a 7^b, which form side clamps adapted to bend 25 over the flanges of the I-beams, as clearly shown in Fig. 10.

In the manufacture of metallic studs or partition-supports it is usual to make them a standard length. In my construction of stud 30 the same may be also of the standard length; but to provide for its use for partitions of greater length I provide a supplemental telescopic section adapted to be detachably joined with the upper end of the member 1. This 35 supplemental section (designated by 10) has substantially the same cross-sectional form of the member 1; but to provide for a rigid joint between the two members, so as not to weaken the complete stud, the angle sides 10^a of the 40 central or U-shaped part of the member 10 are slotted longitudinally, as at 10^b, to produce turned flanges 10^c, adapted to ride over the edges 1^c of the member 1, as clearly shown in Fig. 6. By thus joining the two members 45 the part 10 can be readily slid up or down to lengthen or shorten the stud to a height desired, and by reason of the member 10 extending under the same part of member 1 and the flange 10^c fitting over the edges 1^c 50 of the member 1 the parts are joined firmly to form a continuous member, and buckling of the same at the joint is entirely overcome. The sides of the member 10 are also slotted, as at 10^d, to provide the lath-securing 55 clips, as shown, and the said sides are also extended to form strap members 10^e 10^f for clamping upon and bending over the I-beam flanges or for making fast to ceiling-beams when of wood.

60 My metallic stud is intended to serve as a substitute for the usual wooden partition-stud, and in the practical use the said studs may be set sixteen inches (more or less) apart, as usual.

65 To provide for strengthening the studs, especially against buckling in a lengthwise direction, I provide the base of the U-shaped

body with horizontal slots 1^f, adapted to receive tongues or projecting lips 15^a of supplemental metal members 15. This latter 70 member 15 in the simplest application of my invention, especially where the studs are closely set, need not be used; but when the studding is widely separated said braces 15 will serve to take up the longitudinal strain 75 and maintain the studs in their proper position.

In Figs. 12 and 12^a I have shown how my improved metallic studs are arranged for sustaining the guide-rail of sliding doors or partitions. For this purpose the cross-brace, in the nature of a plate 16, to which the hanger 17 is secured and made to project sufficiently below the plate to allow for a proper clearance of the roller or slide member (not shown) 85 on the door, and to firmly secure the plate 16 it has two or more bendable-clip ends 16^a at each end to engage the slots in the opposite studs 1, as shown.

While I have described my improved stud 90 as more especially adapted for fireproof buildings, it is obvious the same may be used as a partition for ordinary buildings and made to support wooden laths.

From the foregoing description, taken in 95 connection with the accompanying drawings, it is thought the manner in which my form of metallic stud or supporting member is capable of being used and its advantages will be readily apparent to those skilled in the 100 art to which it appertains.

The construction is such that the same can be economically and conveniently employed for supporting metallic laths for side walls and ceilings and readily made fast in a vertical 105 position and suspended horizontally.

While I prefer to bend the inner or body part of the metal plate in the manner shown and described, said body portion may be corrugated or fluted, and the several minor details of construction may be also slightly modified or varied without departing from the scope of the appended claims.

By constructing the stud members in the manner described it is manifest that when assembled to form partitions air-spaces are provided, which renders the partitions practically sound-proof. This latter feature, so far as I know, has heretofore not been provided in the ordinary types of metallic studding.

Having thus described my invention, what I claim, and desire to secure by Letters Patent, is—

1. A sheet-metal stud, comprising a central corrugated body portion, the free ends of 115 which are bent back in parallel planes to form lath-receiving surfaces, said surfaces having bendable portions to clamp the laths, for the purposes specified.

2. A metallic stud-partition, comprising vertical U-shaped studs, each having supplemental parallel side members, having lath-clamping members, said U-shaped body having slots, and a brace-stud provided with project-

ing tongues at the ends to engage the slots in the vertical studs, said vertical studs having means at the opposite ends for attaching to the ceiling or floor, as set forth.

5. As a new article, a metal stud or supporting member, comprising a body portion **U**-shaped in cross-section, and having its sides bent to form resilient lath-attaching portions, said portions having bendable members adapted to clamp over the laths, for the purposes specified.

10. As a new article, a metal stud or supporting member, comprising a body portion **U**-shaped in cross-section, its free sides having extensions bent to form opposing parallel sides, said sides having diagonal notches, whereby to provide bendable clamp members, for the purposes specified.

15. A metallic stud consisting of a body, **U**-shaped in cross-section, the sides of which have extensions bent to form parallel faces, said sides having bendable clamp members, and a supplemental member slidably mounted thereon, having parallel sides provided with 20 lath-clamp portions, said sides having bendable extensions, for the purposes specified.

25. As a new article, a metal stud or support-

ing member, comprising a main body **U**-shaped in cross-section, the sides of which are extended and bent to form opposite parallel lath-receiving sides, and a detachable supplemental portion, consisting of a **U**-shaped portion, the opposite sides of which are slotted longitudinally, said sides having extensions bent to form opposing lath-receiving sides, 30 the lath-receiving sides of the two parts having lath-clamping members, for the purposes specified.

35. In a metallic studding or partition of the character described, the combination with two 40 studs, each formed of sheet metal and consisting of a **U**-shaped body portion, the sides of which are bent to form opposing parallel sides to form lath-holding surfaces, the cross or base portion of said **U**-shaped body having 45 slots; of a cross member having tongues to engage and be clamped within the slots of the **U**-shaped body, and adapted to form a support for a hanger, as set forth.

PAUL BRANDSTEDT.
